UNITED STATES PATENT OFFICE.

HARRY R. BOOZE, OF BUCHANAN, VIRGINIA.

WIRE-STRETCHER.

1,005,802.

Specification of Letters Patent. Patented Oct. 17, 1911.

Original application filed June 14, 1910, Serial No. 566,794. Divided and this application filed October 1, 1910. Serial No. 584,891.

To all whom it may concern:

Be it known that I, HARRY R. BOOZE, a citizen of the United States, residing at Buchanan, in the county of Botetourt and 5 State of Virginia, have invented certain new and useful Improvements in Wire-Stretchers, of which the following is a specification, reference being had to the accompanying drawings.

10 This invention relates to improvements in wire stretchers and has for its object to provide a very simple and efficient device of this character which may be easily and quickly arranged in position upon a fence 15 post to properly stretch the wires preliminary to the stapling of the same to the fence post.

Another object of the invention is to provide a wire stretcher which is adapted for 20 use in combination with a fence wire clamp, the stretcher being arranged upon a fence post and consisting of two primary elements, one of which is engaged with the chains connecting the upper and lower ends 25 of the clamping bars and is pivotally movable upon the other member, and means for holding the first named member against retrograde movement after the wires have been stretched.

30 A still further object of the invention resides in the provision of a very strong and durable wire stretcher which may be constructed at a low cost.

With these and other objects in view, the 35 invention consists in the improved combination and arrangement of parts hereinafter fully described and claimed and illustrated in the accompanying drawing in which is shown a perspective view of my improved 40 wire stretcher arranged in operative position.

Referring in detail to the drawing 5 indicates the wire clamping bars which are adapted to be arranged upon opposite sides 45 of the fence wires W. The manner in which these bars are connected and clamped together upon the fence wire forms the subject matter of a prior application for patent filed by me June 14th, 1910, Serial Number 50 566,794, and of which this application is a division. It will suffice for the purposes of this description to state that these bars are connected together at their upper and lower ends by means of a link chain C which is 55 adapted to be engaged by my improved

stretching device in a manner which will be more fully hereinafter set forth.

The wire stretcher embodied in the present application comprises a main body bar 10 which is arranged adjacent to the fence post P. At one end this bar has an enlargement 11, said end portion being rectangular in form as shown at 10' while the remaining portion thereof is preferably cylindrical. 60 To the end of the cylindrical portion of the bar a hook 12 is secured which is adapted to be engaged with the meshes of the fence wire fabric to support the end of the bar when the stretcher is arranged in operative position. Adjacent to the other or forward end of the bar 10 an arm 13 is secured, said arm being bifurcated at its outer end to form gripping fingers 13'. These fingers are adapted to engage and bite into the fence post P. Upon the enlarged end 11 of the bar 65 a U-shaped member 14 is pivoted upon the pin 15 which extends vertically through the end of said bar. The U-shaped yoke member 14 is formed of two heavy metal bars or arms 14' which are brought together at 70 one of their ends and connected by the bolts or other analogous fastening devices 16. These bolts also extend through the ends of the loops 17 which are disposed upon opposite sides of the connected arms 14. The 75 other ends of the yoke arms extend upon opposite sides of the end of the bar 10 and beyond the edge thereof and have their extremities formed with the hooks 18.

In the loops 17 the end of a lever or 80 handle 24 is inserted by means of which the yoke member 14 may be turned upon its pivot pin 15, the hooks 18 on the ends of a yoke being engaged with the chains C whereby the clamp in which the fence wire 85 fabric is disposed is pulled or extended forwardly beyond the post and the wire stretcher. This pull upon the clamp also serves to bind the opposed edges of the clamping bar upon the fence wires and thus 90 overcome all liability of the wire slipping between the bars.

The enlarged end portion 11 of the bar 10 is provided with a plurality of openings 95 25 any one of which is adapted to receive a pin 26. These openings are arranged in circular series and the pin 26 is inserted therethrough in advance of the yoke arms 14' after the wire has been stretched, to retain the yoke in position upon the bar 10 and 100 110

- prevent its retrograde movement, thus preventing slackening of the fabric and permitting the operator the free use of his hands in the stapling of the wire to the fence post. The hooks 18 are then disengaged from the chain and the stretcher removed. The clamp is then positioned upon the fabric adjacent to the next succeeding fence post and the same operation repeated.
- 10 From the foregoing it will be seen that I have produced an extremely simple and efficient wire stretcher whereby the wires of a fence may be very quickly stretched and stapled to the post. The bar 10 and the parts carried thereby may be moved to any position upon the post so as to stretch the wires both at the top and bottom thereof, thus preventing any portion of the fabric from sagging or giving under severe strains.
- 15 The device is also capable of quick application so that its arrangement in operative position upon the fence post requires but little time, thus greatly lessening the expense and labor involved in the erection of
- 20 the fence. The stretcher is also extremely durable and may be manufactured at a comparatively low cost.

While I have shown and described the preferred embodiment of my invention, it will be understood that the same may be variously modified without departing from the essential feature or sacrificing any of the advantages thereof.

30 It will be noted that by means of a wire stretcher constructed as above described, the wires may be held taut and stapled to the same post upon which the stretcher is arranged.

Having thus described the invention what is claimed is:—

1. A wire stretcher comprising in combination, a bar, means carried by said bar to anchor the same to a fence post, means arranged on one end of said bar to engage a wire fabric, a yoke member pivotally mounted on the other end of said bar, hooks formed on said yoke, a plurality of loops secured to the yoke, an operating member insertible into said loops whereby the yoke is actuated in one direction, and means adjustable in the end of the bar to be engaged by said yoke to prevent its retrograde movement after the wire fabric has been stretched. 40

2. A wire stretcher comprising in combination, a body bar, an element fixed to said bar to engage a stationary object to anchor said bar, a hook secured to one end of said bar to engage the wire fabric, a yoke member extending upon opposite sides of the bar at the other end thereof, a pivot bolt 55 extending through said bar and the yoke member, hooks formed upon said yoke member, means carried by said yoke member for the connection of an actuating element thereto, said body bar having a plurality 60 of openings therein, and a pin insertible in any one of said openings to prevent retrograde movement of the yoke member after the fabric has been stretched. 65

In testimony whereof I hereunto affix my 70 signature in the presence of two witnesses.

HARRY R. BOOZE.
